CLAIM

The ornamental design for an electronic cigarette body, as shown and described.

DESCRIPTION

The file of this patent contains at least one drawing executed in color. Copies of this patent with color drawings will be provided by the Office upon request and payment of the necessary fee.

FIG. 1 is a perspective view of an electronic cigarette body;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a reference view, which shows the claimed design being attached to an electronic cigarette cartridge.

The translucent grey overlay and the broken lines in the drawings depict portions of the electronic cigarette body and environment that form no part of the claimed design.
